CIRCUIT INTERRUPTER

Clinton L. Denault, Sharpsville, Pa., assignor to
Westinghouse Electric Corporation, East Pittsburgh, Pa., a corporation of Pennsylvania

Application June 29, 1944, Serial No. 542,688

6 Claims. (Cl. 200—150)

1

This invention relates to circuit interrupters in general, and, more particularly, to arc-extinguishing structures therefor.

A general object of my invention is to provide an improved circuit interrupter in which more effective performance is achieved at increasing economical operation. This is obtained by providing an improved construction wherein the fluid blast principle is used in a way which will permit a wide range of currents to be handled in a given sized structure without the use of excessive fluid quantities or fluid driving pressures.

A more specific object of my invention is to provide an improved circuit interrupter in which a discharge outlet is provided adjacent the established arc and to provide improved valve means, controlling the discharge outlet which will be responsive to the pressure in the arc region. Preferably the improved valve means comprises guide means for directing fluid toward the arc in which the opening movement of the guide means will serve to decrease the quantity of fluid directed toward the arc to thereby prevent the generation of excessive pressures within the arc region.

Further objects and advantages will readily become apparent upon the reading of the following specification taken in conjunction with the drawing in which:

Figure 1 is a vertical sectional view of a circuit interrupter embodying my invention and shown in the closed circuit position, the arc-extinguishing structure being shown in full elevation;

Fig. 2 is a vertical sectional view through the improved arc-extinguishing structure of Fig. 1, the parts being shown in the partly open circuit position; and

Fig. 3 is a modified type of arc-extinguishing structure which may be substituted for the arc-extinguishing structure of Fig. 1.

Referring to the drawing and, more particularly, to Fig. 1 thereof, the reference numeral 1 designates a tank filled to the level 2 with a suitable arc-extinguishing fluid 3, in this instance circuit breaker oil. Depending from the cover 4 of the tank 1 are two insulating bushings 5, 6 through which extend terminal studs 7, 8. Threadedly secured to the lower end of the terminal stud 7 is a bracket 9 having secured thereto a slider contact 10, making contacting engagement with the conducting portion 11 of the movable contact, generally designated by the reference numeral 12. The upper portion 13 of the movable contact 12 is formed of insulating material and is vertically actuated in a reciprocal

2

manner during the opening and closing operations by suitable mechanism (not shown).

Insulating brackets 14, 15 rigidly support within the tank 1 the arc-extinguishing structure, generally designated by the reference numeral 16. Movable through the bottom plate 17 of the tank 1 through suitable packing means 18, is an operating rod 19 at the upper end of which is secured a piston 20 movable within a piston chamber 21 and constituting fluid moving means. Preferably flap valves 22 are provided to permit a unidirectional flow of fluid through apertures 23 provided in the piston 20. Thus, during the opening operation of the circuit interrupter when the piston 20 is forced upwardly, the flap valve 22 will remain closed. During a subsequent resetting of the piston 20, as it moves downwardly the flap valves 22 will open to permit a unidirectional flow of oil to take place through the apertures 23.

Preferably the opening movement of the movable contact 12 is synchronized with upward movement of the piston 20. In one arrangement, by way of example, this may be accomplished by employing a lever 77 pivoted to a fixed pivot 78. The lever 77 has its left-hand end, as viewed in Fig. 1, pivotally connected to the insulating portion 13 at 79. The right-hand end of the lever 77 is pivotally connected at 80 to a link 81, the lower end of which is pivoted at 82 to a lever 83. The lever 83 is pivoted on a fixed pivot 84. The left-hand end of lever 83, as viewed in Fig. 1, is pivotally connected at 85 to the lower end of the operating rod 19.

Thus upward opening movement of the movable contact 12 by suitable means, not shown, simultaneously causes upward movement of the piston 20 to force fluid toward the established arc. During the downward closing movement of the movable contact 12, the piston 20 is moved downwardly to be charged.

Referring, more particularly, to Fig. 2 which illustrates an enlarged vertical sectional view through the arc-extinguishing structure 16, it will be observed that the casing 24 of the arc-extinguishing structure 16 is formed of insulating material and has an annular recess 25, formed at its upper end. Secured between insulating brackets 14 within the annular recess 25, is a ring-shaped member 26 which cooperates with the recess 25 to form an annular discharge outlet or venting means, generally designated by the reference numeral 27. The annular discharge outlet or annular discharge means 27 permits a discharge or exhausting of fluid away from the arc 28 drawn between the movable contact 11

and the relatively stationary contact 29 within an elongated generally cylindrical substantially enclosed arc passage 86.

An aperture 30 is centrally provided in the ring-shaped member 26 and has an inwardly extending flange 31 disposed at its lower end. Slidably movable within the aperture 30 is a sleeve valve 32 constituting valve means responsive to the pressure within the arc passage and controlling the venting means 27. It may be either of insulating or metallic material but is herein shown as being of insulating material, having a flange 33 biased against the flange 31 by a compression spring 34, encircling the sleeve valve 32. The upper end of the compression spring 34 seats against a ring 35 secured by screws 36 within a recess 37 provided in the ring-shaped member 26.

It will thus be apparent that the sleeve valve 32 controls the exhausting of fluid out of the arc-extinguishing structure 16 through the annular discharge outlet 27, the valve 32 being responsive to the pressure within the arc region and also responsive to the velocity of the fluid.

An annular recess 38 is provided at the lower end of the casing 24. An insulating bottom plate 39 is secured by bolts 40 to the casing 24. Disposed between the casing 24 and the bottom plate 39, is a conducting spider member 41 having apertures 42 provided therein, the spider 41 having an upstanding portion 43 internally threaded to rigidly support in place a conducting cylindrical member 44 which, in the closed circuit position of the interrupter, makes sliding contacting engagement with the movable contact 11. The relatively stationary contact 29 is biased upwardly by a compression spring 45 so that a flange 46, integrally formed with the stationary contact 29, makes abutting engagement with a shoulder 47. Thus, in the closed circuit position the conducting cylindrical member 44 serves to carry the current through the interrupter, whereas during the opening operation, the stationary contact 29 remains in following engagement with the movable contact 11 until the flange 46 strikes the shoulder 47, at which time the lower terminal of the arc 28 attaches to the upper end of the stationary contact 29. Thus the stationary contact substantially encloses the arc passage 86 at the lower end. As a result, no arcing takes place between the cylindrical member 44 and the movable contact 11.

The spider 41 has a terminal portion 48 to which is electrically attached a cable 49 by a screw 50. The upper end of the cable 49 is secured by nuts 51 to the lower end of the terminal stud 8.

From the foregoing description, it will be apparent that in the closed circuit position of the interrupter shown in Fig. 1, the electrical circuit therethrough comprises terminal stud 7, conducting bracket 9, slider contact 10, conducting portion 12 of movable contact 11, cylindrical member 44, spider 41, terminal portion 48, cable 49, to terminal stud 8.

Inserted within the recess 38 against a shoulder 52, is a ring-shaped plate 53 composed of insulating material, having a central aperture 54, and having a plurality of outer apertures 55 formed therein. The plate 53 is maintained in place by a resilient ring clip 56 disposed in an annular groove 57 provided in the casing 24. The cylindrical member 44 has at its upper end a radially outwardly extending horizontal portion 58 which cooperates with the plate 53 to form an inwardly extending inlet passage, designated by the refer-

ance numeral 59. Also the plate 53 cooperates with the upper end of the recess 38 which extends inwardly to form a ring-shaped plate portion and thereby to form a second radially inwardly extending inlet passage, designated by the reference numeral 60. I provide the outer periphery of the horizontal portion 58 with a downwardly depending flange portion 61 to cooperate with the upper portion of the recess 38 to provide an annular inlet passage, generally designated by the reference numeral 62 in Fig. 2.

The operation of the embodiment of my invention shown in Figs. 1 and 2 will now be explained. During the opening operation, suitable means (not shown) causes both upward movement of the movable contact 11 and upward movement of the operating rod 19 and piston 20 by the aforesaid linkage. An arc 28 is established between the contact 29 and the movable contact 11, the upward movement of the piston 20, flap valves 22 remaining closed, serving to force fluid, in this instance oil, upwardly through the apertures 42 in spider member 41, upwardly through the annular inlet passage 62, and radially inwardly through the passages 59, 60 toward the arc 28. After contacting the arc 28, the fluid exhausts out through the discharge outlet 27, raising the sleeve valve 32 to an extent depending upon the pressure within the arc region. Following interruption, the movable contact 11 preferably moves out of the arc-extinguishing structure 16 to a position shown by the dotted line 63 in Fig. 1 to provide an isolating gap in the electrical circuit.

By the above construction, it will be apparent that I have provided a circuit interrupting structure where use is made of the fluid blast principle in a way which will permit a wide range of currents to be handled in a given sized structure without the use of excessive fluid quantities or fluid driving pressures. The arc 28 is drawn within an arc passage 86 which is almost completely closed on the discharge side by the sleeve valve 32, spring-biased to its lower position. This valve 32 is responsive to both pressure and velocity. With this arrangement, a wide range of currents can be handled in the arc chamber without having excessive pressures in the arc zone at the high currents, nor having excessive fluid loss at the low currents. As an additional feature, the control of the arc discharge area contributes a self-generated pressure control effect in the arc zone, where a desirable moderate pressure is generated and maintained by the interaction of the fluid flow and discharge valve movement.

The embodiment of my invention, shown in Fig. 3, is generally similar in some constructional features with the embodiment shown in Fig. 2; consequently, similar reference numerals have, where possible, been employed. However, in this embodiment of my invention, the conducting cylindrical member 44 of Fig. 2 has been omitted and in its place has been provided an insulating cup-shaped member 64 constituting second valve means which serves to guide an insulating ring-shaped member 65 which supports, by bolts 66 and their spacer sleeves 67, a plurality of spaced insulating ring-shaped plates 68, cooperating to provide a plurality of inlet passages, designated by the reference numeral 69 and disposed in superimposed relation axially along the path of movement of the movable contact 11. The spaced plate structure is operatively connected to the first valve means 70 hereinafter described.

The upper ends of the bolts 66 are threadedly secured to an insulating inverted cup-shaped movable first orifice-shaped valve member 70, having the upper portion 71 thereof of such configuration that it controls by valve action the discharge outlet or venting means 27. The ring-shaped member 26 forms a stationary valve seat for the first valve means 70 in this embodiment of my invention. The cup-shaped member 70 is guided by a cylindrical portion 72 of the casing 24. The region 75 below the ring-shaped member 65 is connected by conduit 76 to the region outside of casing 24 to eliminate back-pressure on member 65.

In the embodiment of my invention shown in Fig. 3, an additional feature is incorporated in the structure. In this case the discharge duct valve is a part of the fluid duct guide and is so arranged that as the pressure in the arc chamber increases, the fluid entrance ducts 69 will be moved downwardly with respect to the fixed contact 29, so that, as the discharge outlet 27 opens up during high pressure, the fluid inlet passages 69 will be blocked by the second valve means 64 to a greater and greater extent, as the discharge opening 27 increases. This serves to reduce the quantity of oil flowing into the high current arcs, thereby preventing the generation of excessive pressures. It is probable that a definite minimum quantity of oil will be necessary. The stop 73 controls that feature.

From the foregoing description of the embodiment shown in Fig. 3, it will be apparent that I have provided an improved circuit interrupting structure in which annular guide means, generally designated by the reference numeral 74, and comprising the plates 68 and cup-shaped member 70, are provided which have the additional function of serving as a valve for the annular discharge means 27. The downward movement of the annular guide means 74 not only serves to open up the discharge means 27, but also serves to decrease the number of inlet passages 69 available, thereby decreasing the quantity of fluid directed upwardly by the piston 20 toward the arc 28.

Although I have shown and described specific structures, it is to be clearly understood that the same were merely for the purpose of illustration and that changes and modifications may readily be made therein by those skilled in the art without departing from the spirit and scope of the appended claims.

I claim as my invention:

1. In a circuit interrupter, means including a plurality of spaced ring-shaped plate members defining an elongated generally cylindrical substantially enclosed arc passage, a relatively stationary contact disposed at one end of the arc passage and substantially blocking the same at this end, a movable rod-shaped contact separable from the stationary contact to draw an arc through the arc passage, fluid moving means for forcing fluid radially inwardly toward the arc between the spaced ring-shaped plate members, venting means disposed adjacent the other end of the arc passage, and valve means responsive to the pressure within the arc passage and disposed adjacent the other end of the substantially enclosed arc passage to control the exhaust of fluid out of the venting means.

2. In a circuit interrupter, means including a plurality of relatively fixed spaced ring-shaped plate members defining an elongated generally cylindrical arc passage, means for establishing

an arc axially within the arc passage, means substantially enclosing the arc passage at one end thereof, fluid moving means for moving fluid radially inwardly between the spaced ring-shaped plate members along the arc passage, venting means disposed adjacent the other end of the arc passage, and valve means responsive to the pressure within the arc passage to control the exhaust of fluid out of the venting means.

3. In a circuit interrupter, means defining a substantially enclosed arc passage, means for establishing an arc within the arc passage, venting means disposed adjacent one end of the arc passage, valve means responsive to the pressure within the arc passage for controlling the exhaust of fluid out of the arc passage through the venting means, means at least partially of insulating material defining a plurality of fluid passages operatively connected to the valve means, second valve means for successively closing the fluid passages upon continued opening movement of the first-mentioned valve means, and fluid moving means for forcing fluid through the fluid passages into the arc passage to effect the extinction of the arc established therein.

4. In a circuit interrupter of the fluid type, means defining a substantially enclosed arc passage, means including a rod-shaped movable contact for establishing an arc within the arc passage, means defining a stationary valve seat, a movable orifice-shaped valve, means biasing the movable orifice-shaped valve against the stationary valve seat to make the valve responsive to the pressure within the arc passage, spaced plate structure secured to and movable with the movable valve to define a plurality of fluid passages spaced axially along the arc passage, means for forcing fluid through the fluid passages into the arc passage to effect extinction of the arc therein, and relatively stationary valve structure for successively blocking off the fluid passages upon continued opening movement of the movable valve, the arrangement functioning to reduce the quantity of fluid directed into the arc passage upon the attainment of excessive pressure therein.

5. In a circuit interrupter, means defining a substantially enclosed arc passage, means closing the arc passage adjacent one end thereof, means for establishing an arc within the arc passage including a rod-shaped movable contact movable toward the other end of the arc passage, venting means for the arc passage disposed adjacent the other end of the arc passage, valve means responsive to the pressure within the arc passage for controlling the venting means and including a movable valve, annular guide means defining a plurality of radially inwardly extending inlet passages disposed in superposed relation axially along the path of movement of the movable contact and secured to and movable with the movable valve, second valve means for successively closing the inlet passages upon continued opening movement of the movable valve, and fluid moving means for forcing fluid through the passages into the arc passage to effect extinction of the arc therein.

6. In a circuit interrupter, means defining a substantially enclosed arc passage, means for establishing an arc within the arc passage, venting means disposed adjacent one end of the arc passage, valve means including an orifice-shaped movable valve responsive to the pressure within the arc passage for controlling the exhaust of

fluid out of the arc passage through the venting means, a plurality of spaced ring-shaped insulating plates secured to and movable with the movable valve, means for forcing fluid radially inwardly between the plates into the arc passage, and a relatively fixed cup-shaped member disposed in surrounding relation to the plates so that as the movable valve opens the plates progressively enter the relatively fixed cup-shaped member, the arrangement thus functioning to diminish fluid flow toward the arc as the pressure increases to open the movable valve.
